CLAIM

The ornamental design for a billiard training aid, as shown and described.

DESCRIPTION

FIG. 1 is a perspective view of a billiard training aid showing my new design;

FIG. 2 is a top plan view thereof;

FIG. 3 is a bottom plan view thereof;

FIG. 4 is a right side elevational view thereof;

FIG. 5 is a front elevational view thereof; and

FIG. 6 is a rear elevational view thereof.

The broken line showing of golf ball in FIG. 5 is for illustrative purposes only and forms no part of the claimed design.

FIG. 1

FIG. 2

FIG. 3

FIG. 4

FIG. 6

FIG. 5
